United States Patent Office

Des. 205,201
Patented July 5, 1966

205,201

BOAT CONTROLLER

Maurice H. Butler, 807 E. Tucker Blvd., Arlington, Tex.

Filed Oct. 20, 1965, Ser. No. 87,612

Term of patent 14 years

(Cl. D71—1)

Fig. 1

Fig. 2

Fig. 3

FIG. 1 is a front elevational view of a boat controller embodying my new design;

FIG. 2 is a right side elevational view thereof; and
FIG. 3 is a left side elevational view thereof.

I claim:

The ornamental design for the boat controller, as shown.
